UNITED STATES PATENT OFFICE.

FREDERICK LOBL, OF MIDDLEBORO, MASSACHUSETTS.

STOPPER FOR CONTAINERS.

Application filed December 30, 1926. Serial No. 158,003.

This invention relates to improvements in stoppers for containers generally, and is intended particularly to provide an effective and easily applied closure for containers or receptacles such as hot-water bottles, ice-bags and fountain syringes. While the disclosure is applicable to such particular use, it is obvious that it may be used to equal advantage with all kinds of bottles, jars, and containers where it is desirable or necessary to use a stopper, which will provide an airtight or hermetic closure and which can be easily applied and removed, i. e., without any great physical effort.

The details of the disclosure are illustrated in the accompanying drawings which form a part of the specification, and in which:

Fig. 1 is a side-elevation of the stopper as applied to a hot-water or ice-bag;

Fig. 2 is a partial-sectional view of the stopper construction with one form of washer used in the assembly;

Fig. 3 is a bottom-plan view of the stopper with a portion of one side broken away to show the interior construction;

Fig. 4 is a partial-sectional elevation of the washer shown in Fig. 2;

Fig. 5 is a sectional view similar to that of Fig. 2, but with a modified form of washer construction.

Fig. 6 is a side elevation of the stopper construction as modified for use with a fountain syringe;

Fig. 7 is a partial sectional elevation of the construction of Fig. 6;

Fig. 8 is a bottom plan view of the construction of Fig. 6; and

Fig. 9 is a perspective view of the washer element.

Referring to the figures of Sheet 1 of the drawings, the body-portion 1 of the stopper comprises a hollow member of thin sheet metal which may be pressed or spun into the desired shape with threaded side-walls, and an outwardly and upwardly flaring flange 2 at its upper edge. The top element of Figs. 1, 2 and 5 comprises a molded or otherwise formed disc 3, which may be of rubber or other suitable plastic heat-insulating material. The peripheral portion of the cover-piece or disc 3 is reduced in thickness as at 4 and is surrounded and reinforced by an in-turned flange on the top of the clamping ring 5. A metallic disc 6 backs the molded

element 3 on its under surface, and is secured thereto by means of the hollow rivet 7 which is positioned centrally of the stopper and through which passes a cotter-pin 8, or similar device, with its eye extending above the disc 3. The eye of the cotter-pin affords a convenient means for connecting a chain or cord to the stopper to effect a swivel connection, so that the stopper may be turned in the operation of applying it to or removing it from a container without twisting or kinking the attached chain or cord.

The clamping-ring 5, between its upper and lower flanges, secures together the body member 1 and the disc 3, and in addition engages the outer edge of the washer 9 and holds the same firmly in the desired position and in contact with the flange 2 of the body member 1.

In Fig. 2, the washer 9 is of a special cross-section, illustrated more completely in Fig. 4, and the clamping action of the ring 5 somewhat distorts this cross-section, bringing the upper surface of the rounded portion of the washer into contact with the flange 2, while the major portion of the flat under-surface of the washer is inclined inwardly and downwardly to constitute a conical sealing surface. Preferably, this conical surface should contact, for sealing, with a similarly sloped surface, on the neck of the container, as is shown in dotted lines in Fig. 1; but this is not essential, and the stopper will make an effective sealing contact with any circular opening, the diameter of which is within the limits of the sloping contact area of the washer 9. The backing flange 2 is resilient and therefore yields somewhat to sealing pressure, allowing the washer to readily conform to any slight irregularities in the sealing surface of the receptacle, and when sufficient pressure is applied to the stopper, as in sealing, the entire flange 2 will be somewhat flexed upwardly, so that a constant pressure is thereby exerted by the flange 2, which tends to maintain the washer in tight and sealing contact with the neck of the container to which it is applied.

The washer construction of Fig. 5, while of different cross-section, is designed to present the same, or substantially the same, lower conical contact or sealing surface, and with its entire upper surface pressed against the flexible flange 2.

The air space within the hollow body member 1, together with the cover 3, which is a layer of plastic material of substantial thickness, constitute effective heat insulation of the contents of the receptacle, and when the stopper is used with a hot-water bottle or bag, the exposed parts of the stopper, by reason of its insulating properties, are prevented from becoming so hot as to burn the user or to be difficult to handle.

In Figs. 6 and 9 of the drawings, the principles of construction above described are illustrated as applied to a stopper to be used with a fountain syringe, in which use 15 a passage for liquid through to the center of the stopper is provided. Fig. 7 shows the detail of this construction in sectional-elevation. The body member 1 with flange 2, the clamping ring 5, and washer 9, are 20 substantially the same as described in connection with Figs. 1-5. In lieu of the plastic cover-piece 3, a pressed metallic cover-piece 10 is employed, having a flat marginal flange 11 which is engaged by the clamping 25 ring 5. A flat ring-washer 12 of suitable fibrous material, is interposed between the under surface of the flange 11 and the flange 2 of the body-member, so that when the stopper-elements are assembled and clamped 30 securely together between upper and lower flanges of the ring 5, the top and body-member of the stopper will be separated from actual metallic contact to retard the conduction of heat and the possibility of leakage. 35 between the elements is substantially minimized. A short length of metallic tubing 13 extends through the central part of the stopper construction, through an opening in the bottom of the body element 1, and extending for a short distance beyond the cover-plate 10 to provide a convenient means 40 for the attaching of a section of rubber hose which is a necessary part of the equipment of a fountain syringe. It will be apparent 45 that the sealing action of this construction is the same as described in connection with the other figures, and that its method of use and advantages are substantially the same.

Slight changes in the mechanical details 50 of the device, obviously can be made without departure from the generic disclosure herein made.

What I claim to be new is:

1. In a stopper for containers comprising 55 a hollow metal body portion with a laterally projecting circular flange intermediate the ends of the stopper and near the upper end thereof to form a flexible resilient follower, an annular washer encircling the body portion, and means consisting of an outer clamping ring for permanently attaching the washer to the stopper so that the washer 60 is firmly clamped on one side against the under surface of the circular flange while 65 presenting on its other side a downwardly

and inwardly inclined conical sealing surface.

2. In a stopper for containers comprising a hollow cylindrical body portion of sheet metal which is formed into cup-shape with 70 its side walls threaded and having an outwardly and upwardly inclined circular flange at its upper edge, a top or cover plate for the body portion consisting of a circular disk which extends to cover the body portion and its projecting flange, a washer encircling the body portion and beneath the under surface of the flange thereof, and an outer encircling ring having clamping 75 flanges which fasten together the elements 80 of the stopper with the washer permanently secured thereto being held against the projecting flange of the body portion and presenting on its under side a downwardly and inwardly inclined conical sealing surface. 85

3. A stopper for containers comprising a cup shaped body portion of sheet metal having its side walls pressed into the form of screw threads, and an outwardly flaring circular flange at its upper edge, a washer encircling the body portion and positioned beneath the flange thereof the washer being of molded elastic material and having a reduced cross section at its outer edge, a top or cover element for the body portion consisting of a circular disk of molded plastic material of sufficient thickness to constitute an effective heat insulator and covering the body portion and its projecting flange, and an outer encircling ring having upper and lower clamping flanges between which the cover, body portion, and washer are assembled and retained in fixed relationship with the washer permanently held against the under side of the projecting flange of the body member and presenting on its under side a downwardly and inwardly inclined conical sealing surface. 95 100

4. A stopper for containers as set forth in claim 3, in which the cover element is apertured at its center to receive a swivel connector. 110

5. A stopper for containers comprising a hollow metallic body portion, and a cover therefor consisting of a relatively thick disk of heat insulating material, a washer encircling the body portion and positioned beneath the outer edge of the cover and near the top of the body portion, and an outer encircling ring constituting clamping means by which the washer, body portion and cover are permanently secured together to constitute the stopper, the washer being pressed against the body portion and retained in such position that its underside presents a downwardly and inwardly sloping conical sealing surface. 115 120 125

6. In a stopper for containers a body portion having an outwardly extending annular flange, an annular washer encircling the 130

body portion beneath the flange, said washer having a substantially flat lower face, an annular bead on its upper face, and an outwardly extending peripheral flange, and means for clamping the flange of the washer to the flange of the body portion at their outer edges, whereby the washer is held against the said flange with its lower face presenting a downwardly and inwardly inclined conical sealing surface. ¹⁰

In testimony whereof I hereunto affix my signature.

FREDERICK LOBL.
